OR D16,143 EX

DESIGN.

C. C. E. VAN ALSTINE.

HAIR CRIMP.

No. 16,143.

Patented June 30, 1885

UNITED STATES PATENT OFFICE.

CORNELIUS C. E. VAN ALSTINE, OF PATERSON, NEW JERSEY.

DESIGN FOR A HAIR-CRIMP.

SPECIFICATION forming part of Design No. 16,143, dated June 30, 1885.

Application filed December 2, 1884. Term of patent 3½ years.

To all whom it may concern:

Be it known that I, CORNELIUS C. E. VAN ALSTINE, a citizen of the United States, residing at Paterson, Passaic county, State of New Jersey, have invented and produced a new and original Design for Hair-Crimps, of which the following is a specification, reference being had to the accompanying drawing or photograph, forming a part thereof.

10 Figure 1 shows my newly-designed hair-crimp in elevation and closed, and Fig. 2 shows the parts of Fig. 1 open, these two figures being deemed necessary to fully illustrate my design.

15 The leading feature of my design consists in a scalloped or corrugated outline or periphery.

A is the center of the crimp, which is circular in its general contour. B B are the lids, which are also circular in their outer contour, but have scallops *a*, star-shaped figures *b*, connection *c*, lids B B, and loops *d* upon them, substantially as represented in both figures.

I claim and desire to secure by Letters Patent—

20 In a design for a hair-crimp, the scalloped or corrugated outline or periphery *a a a*, star-shaped figures *b b b*, connections *c c*, lids B B, and loops *d d*, as set forth.

CORNELIUS C. E. VAN ALSTINE.
